UNITED STATES PATENT OFFICE.

EDWARD G. DESOE, OF WEST SPRINGFIELD, MASSACHUSETTS, ASSIGNOR TO THE WESTINGHOUSE AIR BRAKE COMPANY, OF PITTSBURG, PENNSYLVANIA, A CORPORATION OF PENNSYLVANIA.

AUTOMATIC SANDING APPARATUS FOR FLUID-PRESSURE BRAKES.

No. 899,246.

Specification of Letters Patent.

Patented Sept. 22, 1908.

Application filed February 6, 1907. Serial No. 356,030.

To all whom it may concern:

Be it known that I, EDWARD G. DESOE, a citizen of the United States, residing at West Springfield, in the county of Hampden and State of Massachusetts, have invented new and useful Improvements in Automatic Sanding Apparatus for Fluid - Pressure Brakes, of which the following is a specification.

10 This invention relates to automatic sanding apparatus for fluid pressure brakes, and has for its object to provide an improved construction whereby the sanding device will be automatically operated to apply sand to the rails whenever air is admitted to the brake cylinder for applying the brakes.

This invention is especially adapted to be employed in connection with that type of fluid pressure brake apparatus having means 20 for compensating for brake cylinder leakage, whereby the brake cylinder pressure is substantially maintained even when a small amount of air is being drawn from the same, and according to the preferred form my 25 improvement comprises a connection from the brake cylinder or the brake cylinder supply port or passage to the blower of the air sanding device, whereby air will be automatically supplied to the sand blower or 30 ejector each time the brake is applied.

In the accompanying drawing; Figure 1 is a diagrammatic view showing my improvement applied to one form of fluid pressure brake apparatus which may be employed on 35 locomotives or other vehicles; and Fig. 2 is a similar view of a portion of a car brake apparatus embodying a slightly modified form of my improvement.

As shown in Fig. 1, I have illustrated my 40 improvement in connection with that type of fluid pressure brake apparatus wherein fluid, such as air under pressure, is admitted into a small chamber 3, which may be termed the application chamber, when it acts upon 45 an abutment or piston 4 to operate a valve 5 for controlling the supply of air from any suitable source, such as pipe 6 and reservoir 7, through port 8 and pipe 9 to the brake cylinder, or brake cylinders, 10. The opposite 50 side of the piston 4 being exposed to the brake cylinder pressure, it is obvious that the same will actuate the valve 5 to supply substantially the same degree of pressure to the

brake cylinder as is admitted to the application chamber and then close the supply port 8. 55

Any suitable or preferred means may be employed for controlling the supply and release of air to and from the application chamber through a passage or pipe 13.

If desired, an exhaust valve 11 may also be 60 operated by the piston for controlling exhaust ports 12, so that when the air is released from the application chamber the brake cylinder pressure acting on the opposite side of the piston will move the same and 65 valve 11 to open said ports 12 and release the air from the brake cylinder.

When the brake is applied with any degree of air pressure in the brake cylinder, it will be apparent that if the brake cylinder pressure 70 should be reduced below this amount by leakage, or otherwise, the piston will then be actuated by the preponderating pressure of the application chamber to move the valve 5 to open the supply port and admit a sufficient amount of air to compensate for such leakage and to maintain the brake cylinder 75 substantially constant.

According to my improvement, I provide a connection, such as pipe 14, from the brake 80 cylinder or brake cylinder pipe 9 to the air supply pipe 15 leading to the blower of the sanding device, whereby each time air is admitted to the brake cylinder for applying the brakes, it is also supplied through pipe 15 to 85 the sand blower and applies sand to the rails.

In order to furnish air to the sand blower pipe to operate the sanding device at other times than when an application of the brakes is made, an additional pipe connection 17 may 90 be provided leading to a source of air pressure, as reservoir 7, and containing a manually operated valve 18. A check valve 16 is preferably placed in the pipe connection 14 to prevent flow of air to the brake cylinder 95 and exhaust port when the air is being supplied to said blower by means of the hand valve 18.

In Fig. 2 I have illustrated my improvement in connection with another form of 100 brake cylinder maintaining device comprising a chamber 19, to which air at the desired brake cylinder pressure is admitted at the same time that it is applied to the brake cylinder through connection 20 from any desired source or mechanism. The diaphragm

21 then being subject to the opposing pressures of the chamber and the brake cylinder operates the valve 22 to supply any additional air under pressure to the brake cylinder to compensate for leakage or air drawn 5 to operate the sanding device through pipes 14 and 15.

It will now be apparent that where my improvement is used in connection with a fluid pressure brake apparatus having means for maintaining the brake cylinder pressure against leakage, the small amount of air taken from the brake cylinder for operating the sand blower will be readily compensated 10 for and the brake cylinder pressure will not be materially reduced while the sand is being automatically applied to the rails.

While my improvement is particularly adapted to be employed with fluid pressure 20 brake apparatus of this type, it is not limited thereto, but may also be used with any standard or preferred form of air brake equipment.

Having now described my invention, what 25 I claim as new and desire to secure by Letters Patent, is:—

1. The combination with a fluid pressure brake apparatus having a brake cylinder, of a sanding device operated by the fluid supplied to the brake cylinder.
2. The combination with a fluid pressure brake apparatus having a brake cylinder, of a sanding device, and a pipe connection from the brake cylinder to said sanding device.
3. The combination with a fluid pressure brake apparatus having a brake cylinder, of a sanding device, and means whereby air from the brake cylinder is supplied to said sanding device.
4. The combination with a fluid pressure brake apparatus having a brake cylinder, of

a sand blower device, and a pipe for establishing communication from the brake cylinder to the sand blower pipe.

5. The combination with a fluid pressure 45 brake apparatus having a brake cylinder and means for maintaining the brake cylinder pressure, of a sanding device, and means for supplying air from the brake cylinder to said sanding device.

6. The combination with a fluid pressure 50 brake apparatus having a brake cylinder and means for maintaining the brake cylinder pressure, of a sanding device operated by air supplied to the brake cylinder.

7. The combination with a fluid pressure 55 brake apparatus having a brake cylinder and means for maintaining the brake cylinder pressure, of a sand blower pipe, and a pipe connection from the brake cylinder to said sand blower pipe.

8. The combination with a fluid pressure 60 brake apparatus having a brake cylinder, of a sanding device, means for establishing communication from the brake cylinder to the sanding device, a manually operated valve for also supplying fluid to said sanding device, and a check valve for preventing back flow to the brake cylinder.

9. The combination with a fluid pressure 70 brake apparatus having a brake cylinder, of a sand blower pipe, a pipe connection from the brake cylinder to said sand blower pipe, a check valve for said pipe connection, and a manually operated valve for also controlling 75 the supply of fluid to the sand blower pipe.

In testimony whereof I have hereunto set my hand.

EDWARD G. DESOE
